UNITED STATES PATENT OFFICE.

THOMAS O. POTTER, OF BOSTON, MASSACHUSETTS.

DESIGN FOR A BACK-PLATE FOR SUSPENDERS.

SPECIFICATION forming part of Design No. 19,289, dated August 27, 1889.

Application filed April 15, 1889. Serial No. 307,353. Term of patent 7 years.

To all whom it may concern:

Be it known that I, THOMAS O. POTTER, of Boston, in the county of Suffolk and State of Massachusetts, a citizen of the United States, 5 have invented a new and original Design for Suspenders and Braces, of which the following is a specification, reference being had to the accompanying drawing, forming part thereof.

10 The drawing represents a portion of the back of a pair of suspenders or braces, and the design relates to this especial part of the suspenders or braces, and comprises a back plate or piece A, having the concave edges a a' and the pointed upper ends a² a³ and pointed 15 lower ends a⁴ a⁵. This plate or piece may be of any suitable color. There is formed on it or in it a vertical figure in the form of a bar or inlaid figure b. This is of a color contrast- 20 ing with that of the plate or piece A, and there is arranged to cross this bar B the cord

c, which is flat, and which is arranged to intersect above said vertical bar, and the corners c' of which have a rounded finish.

Having thus fully described my invention, 25 I claim and desire to secure by Letters Patent of the United States—

In a design for shoulder-braces or suspenders, the back-plate A, made in one piece, having the concave edges a a', the upper points 30 a² a³, the lower points a⁴ a⁵, the vertical bar b, extending centrally in said plate, but not extended to the top or bottom thereof, the cord c, arranged to cross said vertical bar and parts of the plate adjacent thereto, and extending 35 to a point above and below the bar, and having the circular ornamental caps c' at its points, substantially as described.

THOMAS O. POTTER.
